United States Patent Office

Des. 219,051
Patented Oct. 27, 1970

219,051

SERVING TRAY

Thomas H. Eckdahl, Brooklyn Center, Minn., assignor to
Plastics, Inc., St. Paul, Minn.

Filed Jan. 23, 1970, Ser. No. 21,058

Term of patent 14 years

Int. Cl. D7—99

U.S. Cl. D44—10

FIG. 1 is a top plan view of a serving tray embodying my new design.

FIG. 2 is a side elevational view thereof.

FIG. 3 is a bottom plan view thereof.

FIG. 4 is a sectional view on the line 4—4 of FIG. 1.

FIG. 5 is a sectional view on the line 5—5 of FIG. 1.

I claim:

The ornamental design for a serving tray, as shown.
